TRAFFIC PROTECTION APPARATUS

Andrew J. Sorensen, Edgewood, Pa., assignor to
The Union Switch & Signal Company, Swiss-
vale, Pa., a corporation of Pennsylvania

Application December 11, 1947, Serial No. 791,122

16 Claims. (Cl. 246—219)

1

My invention relates to traffic protection apparatus, and particularly to electromagnetic means located between, but not connected with, the track rails of a stretch of railway track for controlling traffic governing apparatus according as the stretch of railway track is clear or is occupied by a car or train.

This application is a continuation-in-part of my earlier application for Letters Patent of the United States Serial No. 738,886, filed April 2, 1947, for Traffic Protection Apparatus, now abandoned. Figs. 1, 2, and 3 of the present application correspond to Figs. 1, 2, and 3, respectively, of the earlier application.

In railway traffic protection apparatus, it has been found that track circuits for tracks over which train movements are infrequent, such as crossover tracks and spur tracks, at times have poor shunting sensitivity. Also, at some locations, the physical conditions are such that track circuits cannot be installed. In some instances, it is therefore desirable to use other means in addition to, or instead of, a track circuit for detecting the presence of a car or train on a stretch of track.

It is well known that magnetizable bodies affect the distribution of magnetic flux, such as in the earth's field or in the field produced by a magnet. It has also been found that large masses of iron or steel, such as in a railway car, have appreciable residual magnetism.

Accordingly, one feature of my invention is the provision of electromagnetic apparatus, for any given stretch of railway track, having magnetizable core material arranged so that the distribution of the magnetic flux through the core material is varied by a car or train on the stretch of track for effecting corresponding control of traffic governing apparatus.

Another feature of my invention is the provision of periodically operating means for effecting closed circuit control of the apparatus.

I shall describe three forms of apparatus embodying my invention, and shall then point out the novel features thereof in claims.

In the accompanying drawings, Fig. 1 is a diagrammatic view showing one form of apparatus embodying my invention, in which electromagnetic apparatus is located between the rails of a crossover track, and is provided with means for periodically varying the magnetic flux through its core material, and is arranged so that a car or train on the crossover track will produce a constant change in the magnetic flux through its core material; Fig. 2 is a diagram-

5 matic view showing a modified form of the apparatus of Fig. 1, in which the flux through the core material is constant until a car or train arrives but alternating current controlled by the core material is periodically varied; Fig. 3 is a view showing, by a curve, the relationship between flux density and permeability of the magnetizable core material; and Fig. 4 is a diagrammatic view showing another modified form of the apparatus of Fig. 1, in which a magnetic amplifying arrangement is provided.

Similar reference characters refer to similar parts in each of the views.

Referring first to Fig. 1, a stretch of railway 15 is shown comprising two main tracks, designated by the reference characters 1T and 2T, interconnected by a cross-over track 3T through hand-operated switches 1W and 2W. Tracks 1T and 2T are divided by insulated joints 4 to form sections a—b and c—d, respectively, including switches 1W and 2W, respectively.

Each of these track sections may be provided with a track circuit, as shown for section a—b, which includes a suitable source of current, such as a battery 5 connected across the rails adjacent one end of the section, and a track relay, designated by the reference character 1R, connected across the rails adjacent the other end of the section, and which also includes an adjacent portion of track 3T, as is common practice.

30 A signal 1G is shown for governing traffic movements into section a—b, and a signal 2G is shown for governing traffic movements into section c—d. Each of these signals may be of any suitable type, such, for example, as the semaphore or searchlight type.

Two bars, designated by the reference characters 1P and 2P, of magnetizable material having high permeability, are located side by side, but spaced a short distance from each other, between and parallel to the rails of the portion of track 3T which is included in the track circuit for section a—b. In an actual test which was made of this invention, the bars or cores 1P and 2P were laminated, and were on the order of eight inches 40 in length, and were spaced three inches apart. Three separate coils 1i, 2i and 3i are wound around bar or core 1P, and three coils 4i, 5i and 6i, similar respectively to coils 1i, 2i and 3i of core 1P, are wound around bar or core 2P.

45 Windings 1i and 4i of cores 1P and 2P, respectively, are alike, and are constantly energized in series by current from a suitable direct current source, such as a rectifier 1E, which is in turn energized from secondary winding 6 of a

2

power transformer A. Current from rectifier 1E flows through winding 1i of core 1P in a direction which is opposite to the direction in which current flows through winding 4i of core 2P, and hence the adjacent ends of bars 1P and 2P have opposite magnetic poles. The left-hand end of bar 1P, as shown in the drawing, has a south pole, designated by the reference character S, whereas the adjacent end of bar 2P has a north pole, designated by the reference character N.

Windings 2i and 5i of cores 1P and 2P, respectively, are also alike, and are energized in opposite directions with respect to each other, but are only alternately energized, through the 15 front and back points, respectively, of a contact of a code transmitting device CT, from a suitable source of direct current, such as a rectifier 2E, which is in turn energized from a secondary winding 7 of transformer A. Winding 2i is energized in the direction opposite to that in which winding 1i is energized, so that it cancels a portion of the flux produced by winding 1i, while winding 2i is energized. Similarly, winding 5i is energized in the opposite direction to winding 4i, so that while winding 5i is energized, it cancels a portion of the flux produced by winding 4i.

The apparatus is so proportioned that the flux density produced in bars 1P and 2P by the current flowing in windings 1i and 4i, respectively, is at a working point on a steep portion of the curve shown in Fig. 3. The current flowing in windings 2i and 5i is adjusted to lower the flux density only enough to increase the permeability of bars 1P and 2P, respectively, to near the peak of the curve shown in Fig. 3. The apparatus is also so proportioned that a car, upon passing over bars 1P and 2P, will decrease the flux in one of the bars enough to increase the permeability of that bar to near the peak of the curve and will increase the flux in the other bar by a similar amount and correspondingly decrease the permeability of that other bar.

Alternating current is supplied by secondary winding 8 of transformer A through windings 3i and 6i to amplifiers 1M and 2M, respectively. The magnitude of this alternating current is increased or decreased according as the impedance of windings 3i and 6i is decreased or increased, respectively, by the increase or decrease, respectively, of the flux in bars 1P and 2P.

The output current from amplifier 1M is supplied to a rectifier 3E which in turn energizes winding 9 of a code following polar stick relay B1R. The output current from amplifier 2M is supplied to a rectifier 4E which in turn energizes winding 10 of code following relay B1R.

Movement of contacts 11 and 12 of relay B1R to the normal position, in which they are shown in Fig. 1, is effected by energization of winding 10 of this relay, whereas movement of contacts 11 and 12 to the reverse position is effected by energization of winding 9 of relay B1R. If the current supplied to winding 9 of relay B1R were of the same magnitude as that supplied to winding 10 of this relay, the polar contacts 11 and 12 would remain in the position to which they were last previously operated.

The flux is increased alternately in bars 1P and 2P by the current flowing in windings 2i and 5i, respectively, and hence the current is decreased alternately in windings 9 and 10, respectively, of relay B1R, so that contacts 11 and 12 of relay B1R will be normally moving repeatedly

between their normal and reverse positions. A slow release signal control relay AIR will therefore be normally energized from a decoding transformer F, and contact 13 of relay AIR will be closed in a circuit for clearing signal 1G. A similar contact of relay AIR will be closed in a similar circuit for controlling signal 2G.

Each of the rectifiers 1E, 2E, 3E and 4E, rectifier 5E shown in Fig. 2, and rectifiers 6E and 7E shown in Fig. 4 may be of the well-known copper oxide type comprising four half-wave units such, for example, as units 1e, 2e, 3e and 4e, of rectifier 1E, with the low resistance direction of each unit as indicated by its arrow head.

Primary winding 15 of transformer A is energized from a suitable source of alternating current, having terminals BX and CX, which may perhaps have a frequency of the order of 500 to 1000 cycles per second.

Referring now to Fig. 2, another arrangement for controlling relay AIR by variations in flux in bars 1P and 2P is here shown.

Windings 1i and 4i are here energized in opposite directions by direct current from a battery Q. Windings 3i and 6i here constitute two arms of a bridge, and two variable resistors 17 and 19 constitute the other two arms of the bridge. Alternating current of suitable frequency such, for example, as 500 to 1000 cycles per second is supplied to the bridge from a source having terminals BX and CX.

An amplifier M is connected across the midpoints 16 and 18 of the bridge through a filter L which is tuned to the frequency of the alternating current source. Primary winding 20 of a transformer 1F is connected across the opposite side of amplifier M.

A neutral code following relay I is controlled from the secondary winding 21 of transformer 1F through rectifier 5E. Relay AIR is here controlled by contacts 22 and 23 of relay I through a decoding transformer F.

A front contact 24 of a code transmitting device CT is here connected across resistor 19 in one of the arms of the bridge. The apparatus is so proportioned that the impedances of windings 3i and 6i are equal when contact 24 of device CT is open, and resistors 17 and 19 are adjusted to have equal resistances. Therefore, when contact 24 of code transmitter CT is open, the bridge is normally balanced, so that there is no voltage drop across the midpoints 16 and 18 of the bridge, and hence relay I is deenergized. When contact 24 of code transmitter CT closes, however, the bridge becomes unbalanced, so that relay I becomes energized.

Contacts 22 and 23 of relay I therefore normally repeatedly close alternately at their front and back points, in response to the operation of contact 24 of code transmitter CT, so that relay AIR is normally energized and its contact 13 is normally closed in the control circuit for signal 1G shown in Fig. 1, and a similar contact is closed in a control circuit for signal 2G.

When a car or train passes over bars 1P and 2P, causing the flux in one bar to increase and in the other bar to decrease, the bridge is constantly unbalanced, so that relay I is constantly energized, and therefore relay AIR is deenergized and its contact 13 is open in the signal 1G control circuit.

Referring now to Fig. 4, the circuits for windings 1i, 2i, 4i and 5i are here the same as in Fig. 1. Windings 3i and 6i, instead of being energized by the same secondary winding 8 of transformer A

as in Fig. 1, are here energized by separate secondary windings 27 and 29, respectively.

A magnetic amplifying arrangement is provided, including magnetic amplifiers A1M and A2M. Each of the amplifiers A1M and A2M comprises a magnetizable core y , an input winding 32, a bias winding 36, and an output winding 39.

A resistor 33 is connected between positive terminal 30 of rectifier 1E and negative terminal 34 of rectifier 6E.

Input windings 32 of amplifiers A1M and A2M are connected in series with each other across a common terminal 31 which is connected with the opposite terminals 28 and 35 of rectifiers 6E and 7E, respectively, and a midpoint of resistor 33. Bias windings 36 of amplifiers A1M and A2M are energized in series with each other from rectifier 1E.

Winding 9 of relay B1R is energized from secondary winding 38 of transformer A through output winding 39 of amplifier A1M and rectifier 3E. Winding 10 of relay B1R is energized from secondary winding 31 of transformer A through output winding 39 of amplifier A2M and rectifier 4E.

Having described, in general, the arrangement of the various parts of apparatus embodying my invention, I shall now describe the circuits and operation in detail.

As shown in the drawings, all parts of the apparatus are in the normal condition, that is, each of the switches 1W and 2W is in the normal position for a train movement along track 1T or 2T, respectively; each of the signals 1G and 2G is indicating proceed; code transmitting devices CT are repeatedly moving their contacts alternately to their energized and deenergized positions; windings 1i and 4i are constantly energized in opposite directions with respect to each other; windings 2i and 5i in Figs. 1 and 4 are repeatedly energized alternately, and in opposite directions with respect to current in windings 1i and 4i, respectively; alternating current is supplied to amplifiers 1M and 2M through windings 3i and 6i, respectively, in Fig. 1, and is supplied to the bridge in Fig. 2; input windings 32 of amplifiers A1M and A2M in Fig. 4 are energized from secondary windings 27 and 29 of transformer A through windings 3i and 6i; relay B1R in Figs. 1 and 4 is repeatedly closing its contacts 11 and 12 alternately in their normal and reverse positions; relay I in Fig. 2 is repeatedly closing its contacts 22 and 23 alternately at their front and back points; and relays A1R are constantly energized.

I shall assume that, with apparatus arranged as shown in Fig. 1, a trainman reverses switches 1W and 2W, so that a train may proceed over track 3T. I shall assume further that a car or train, when it passes over bars 1P and 2P, adds to the flux in bar 1P produced by winding 1i, and decreases the flux in bar 2P produced by winding 4i.

The circuit by which windings 1i and 4i are energized passes from rectifier 1E, through winding 4i and winding 1i in the opposite direction, back to rectifier 1E, causing the left-hand end of bar 2P, as shown in the drawing, to have a north pole N, and the adjacent left-hand end of bar 1P, as shown in the drawing, to have a south pole S.

Code transmitter CT is constantly energized from a suitable source of current having terminals B and C, and hence its contact 25 is repeatedly closing alternately at its front and back points. With contact 25 of device CT closed at its front point, winding 2i is energized by a cir-

cuit passing from rectifier 2E, through the front point of contact 25, and winding 2i, back to rectifier 2E. When contact 25 closes at its back point, winding 5i is energized by a circuit passing from rectifier 2E, through the back point of contact 25, and winding 5i back to rectifier 2E.

However, with the flux in bar 1P increased, and with the flux in bar 2P decreased, due to the car or train, as assumed, the permeability of bar 1P

10 will be lower than that of bar 2P, and hence the impedance of winding 3i will be lower than that of winding 6i, so that the contacts of relay B1R will be constantly closed in the reverse position. With contacts 11 and 12 constantly closed in one position, no alternating current will be generated in the secondary winding of transformer F, and hence relay A1R will become deenergized, and its contact 13 will be open in the control circuit for signal 1G, so that signal 1G will indicate stop as long as the car or train remains adjacent bars 1P and 2P.

With the apparatus as shown in Fig. 2, windings 1i and 4i are constantly energized by current passing from battery Q, through a variable resistor 26, winding 4i, and winding 1i back to battery

25 Q. Alternating current passes from terminal BX, through winding 3i, point 16 of the bridge, and variable resistor 17 to terminal CX. Alternating current also passes from terminal BX, through winding 6i, point 18 of the bridge, and variable resistor 19 to terminal CX. When contact 24 of code transmitter CT is open, the current flowing through these two circuit paths is the same, and hence there is no voltage drop between midpoints 35 16 and 18 of the bridge. Each time that contact 24 closes, however, current is shunted around resistor 19, causing a voltage drop to be produced across midpoint 16 and 18 for energizing primary winding 29 of transformer 1F through amplifier 40 M and filter L.

If a car increases the flux in bar 1P and decreases the flux in bar 2P, as previously assumed, however, the bridge will be permanently unbalanced as long as the car remains in the position to have this influence on bars 1P and 2P, and hence transformer 1F will be continuously energized, causing relay I in turn to be continuously energized, and therefore relay A1R will be deenergized and its contact 13 will be open in the circuit for signal 1G, and a similar contact of relay A1R will be open in a similar circuit for controlling signal 2G.

With apparatus as shown in Fig. 4, the circuit for energizing the input windings 32 of amplifiers A1M and A2M from secondary winding 27 of transformer A passes from the left-hand end of winding 27, as shown in the drawing, through winding 3i of core 1P, asymmetric unit 1e of rectifier 6E, terminal 28 of rectifier 6E, terminal

60 31, input windings 32 of amplifiers A1M and A2M, resistor 33, terminal 34 of rectifier 6E, and asymmetric unit 2e of rectifier 6E, back to secondary winding 27 of transformer A. The circuit for energizing input windings 32 of amplifiers A1M and A2M from secondary winding 29 of transformer A passes from the left-hand end of winding 29, as shown in the drawing, through winding 6i of core 2P, asymmetric unit 1e of rectifier 1E, terminal 30 of rectifier 1E, resistor 33, input windings 32 of amplifiers A1M and A2M, terminal 31, terminal 35 of rectifier 1E, and asymmetric unit 2e of rectifier 1E, back to winding 29 of transformer A.

It will be noted that the voltages provided by secondary windings 27 and 29, in the circuits just

traced, across resistor 33 and terminal 31 are opposed to each other, so that when these voltages are equal, no current will flow through input windings 32 of amplifiers A1M and A2M. These voltages are equal only during the intervals when contact 25 of code transmitter CT is open at both its front and its back point.

When contact 25 is closed at its front point, the impedance of winding 3i is higher than that of winding 6i, so that current from secondary winding 29 then flows from resistor 33 through input windings 32 to terminal 31. The flux produced in core y of amplifier A2M by its input winding 32 is now in the same direction as the flux produced by bias winding 36 of amplifier A2M, whereas the flux produced in core y of amplifier AIM by its input winding 32 opposes the flux produced by bias winding 36 of amplifier AIM. The magnetic flux in core y of amplifier A2M is therefore of higher magnitude than the flux in core y of amplifier AIM, so that winding 10 of relay B1R is energized from secondary winding 37 of transformer A by current of higher magnitude than winding 9 of relay B1R is energized from secondary winding 38 of transformer A. The circuit for energizing winding 10 from one half of the alternating current wave passes from the left-hand terminal of secondary winding 37 of transformer A, as shown in the drawing, through output winding 39 of amplifier A2M, asymmetric unit 1e of rectifier 4E, winding 10 of relay B1R, and asymmetric unit 2e of rectifier 4E, back to secondary winding 37. The circuit for energizing winding 10 by the opposite half wave from secondary winding 37 can be readily traced on the drawing. Contacts 11 and 12 of relay B1R therefore become closed in their normal positions.

When contact **25** of code transmitter CT is closed at its back point, the impedance of winding **6i** is higher than that of winding **3i**, so that current from secondary winding **27** of transformer A then flows from terminal **31** through input windings **32** of amplifiers A1M and A2M to resistor **33**. The flux produced in core *y* of amplifier A1M by its input winding **32** is now in the same direction as the flux produced by bias winding **36** of amplifier A1M, whereas the flux produced in core *y* of amplifier A2M by its input winding **32** now opposes the flux produced by bias winding **36** of amplifier A2M. The magnetic flux in core *y* of amplifier A1M is therefore of higher magnitude than the flux in core *y* of amplifier A2M, so that winding **9** of relay B1R is now energized from secondary winding **38** of transformer A by current of higher magnitude than winding **10** of relay B1R is energized from secondary winding **37** of transformer A. Contacts **11** and **12** of relay B1R therefore become closed in the reverse position.

If a car or train increases the magnetic flux in bar 1P and decreases the magnetic flux in the bar 2P, as previously assumed, the impedance of winding 6i will be constantly higher than that of winding 3i, so that contacts 11 and 12 of relay B1R will be constantly closed in their reverse or right-hand position, as shown in the drawing. Relay A1R, controlled by relay B1R, as shown in Fig. 1, will therefore be deenergized, causing signals 1G and 2G to indicate stop.

Although I have herein shown and described only three forms of apparatus embodying my invention, it is understood that various changes and modifications may be made therein within the scope of the appended claims without de-

parting from the spirit and scope of my invention.

Having thus described my invention, what I claim is:

- 5 1. In traffic protection apparatus for a stretch
of railway track including a railway signal, the
combination comprising, two bars of magnetizable
material having high permeability and ar-
ranged parallel to each other between the rails
10 of said stretch of track, a magnetizing coil for
each of said bars energized by direct current and
arranged so that a given end of one of said bars
is the north pole of a magnet and the adjacent
15 end of the second bar is the south pole of a mag-
net and the opposite or south pole end of said
first bar is adjacent the north pole of the second
bar, a second coil for each of said bars energized
by alternating current, coding means for periodi-
20 cally varying the alternating current flowing in
said second coils, and a code following relay con-
trolled by said periodically varied alternating cur-
rent flowing through said second coils for con-
trolling said signal to display a proceed indica-
25 tion if said track is unoccupied but controlling
said signal to display the stop indication if a
train passes over said parallel bars.

2. In traffic protection apparatus for a stretch
of railway track including a railway signal, the
combination comprising, two bars of magnetizable
30 material having high permeability and located
side by side adjacent and parallel to each other
between the rails of said stretch of track, means
for constantly magnetizing one of said bars in a
given direction and for constantly magnetizing
35 the other bar to the same degree in the opposite
direction, a winding around each of said bars
and each of said windings energized by alternat-
ing current, means for periodically varying the
40 magnitude of the alternating current flowing
through said windings, and means controlled by
said alternating current flowing through said
windings for controlling said signal to display a
proceed indication if said track is unoccupied but
45 controlling said signal to indicate stop in response
to a car or train on said stretch of track adja-
cent said parallel bars.

3. In traffic protection apparatus for a stretch
of railway track, the combination comprising, a
pair of bars of magnetizable material located ad-
50 jacent said stretch of track, means for constantly
magnetizing one of said bars in a given direc-
tion and for constantly magnetizing the other
of said bars in the opposite direction, other
means for periodically varying alternately the
55 magnetic flux in said bars, and a code following
relay controlled by said periodic variations of
magnetic flux to periodically close and open its
contacts and controlled by the magnetic flux in
said bars as influenced by a railway vehicle on
60 said stretch of track adjacent said bars to con-
stantly close its contacts.

4. In traffic protection apparatus for a stretch
of railway track, the combination comprising, a
pair of bars of magnetizable material located ad-
65 jacent said stretch of track, means for constantly
magnetizing one of said bars in a given direction
and for constantly magnetizing the other of said
bars in the opposite direction, means for per-
iodically reducing the magnetic flux in said bars
70 alternately, and a code following relay controlled
to periodically close and open its contacts in re-
sponse to said reductions in magnetic flux and
to constantly close its contacts in response to
the magnetic flux in said bars as influenced by

a railway vehicle on said stretch of track adjacent said bars.

5. In traffic protection apparatus for a stretch of railway track, the combination comprising, a pair of bars of magnetizable material located adjacent said stretch of track, means for constantly magnetizing one of said bars in a given direction and for constantly magnetizing the other of said bars in the opposite direction, a winding around each of said bars, and traffic governing means controlled by variations in alternating current supplied through said windings in accordance with variations in magnetic flux in said bars produced by a railway vehicle on said stretch of track adjacent said bars.

6. In traffic protection apparatus for a stretch of railway track, the combination comprising, a pair of bars of magnetizable material located adjacent said stretch of track, means for constantly magnetizing one of said bars in a given direction and for constantly magnetizing the other of said bars in the opposite direction, a winding around each of said bars, a first and a second resistor, a bridge including one of said windings in series with one of said resistors as one side of the bridge and including the other of said windings in series with the other of said resistors as the other side of said bridge, means for passing alternating current through said two sides of said bridge in multiple with each other, means for periodically varying the alternating current passing through one of said resistors, and a neutral code following relay controlled by a circuit connected across the mid points of said bridge one of which is between one of said windings and the resistor with which it is in series and the other of which is between the other winding and the other resistor and periodically energized in response to said variations in alternating current but constantly energized in response to change in magnetic flux in said bars produced by a railway vehicle on said stretch of track adjacent said bars.

7. In traffic protection apparatus for a stretch of railway track, the combination comprising, a pair of bars of magnetizable material located adjacent said stretch of track, means for constantly magnetizing one of said bars in a given direction and for constantly magnetizing the other of said bars in the opposite direction, means for periodically reducing the magnetic flux in said bars alternately, a control winding around each of said bars, and a polar biased code following relay having two windings one of which upon becoming energized by alternating current passing through one of said control windings closes the contacts of said relay in a normal position and the other of which upon becoming energized by alternating current passing through the other of said control windings closes the contacts of said relay in a reverse position in response to variations in magnetic flux in said bars.

8. In combination, two bars of magnetizable material having high permeability and located side by side adjacent and parallel to each other, a magnetizable coil for each of said bars each energized by unidirectional current and arranged so that a given end of one of said bars is the north pole of a magnet and the adjacent end of the second bar is the south pole of a magnet and the opposite or south pole end of said one bar is adjacent the north pole end of said second bar, a second coil for each of said bars each energized by alternating current, coding means for periodically varying the alternating current flowing in said second coils, indication means,

and a code following device controlled by said alternating current in said second coils for controlling said indication means to display normally a given indication but to display a different indication when there is magnetizable body adjacent said bars.

9. In combination, two bars of magnetizable material having high permeability and located side by side adjacent and parallel to each other, 10 means for constantly magnetizing one of said bars in a given direction and for constantly magnetizing the other bar to the same degree in the opposite direction, a winding around each of said bars and each of said windings energized by alternating current, means for periodically varying the magnitude of the alternating current flowing through said windings, indication means, and means controlled by said alternating current after leaving said windings for controlling said 20 indication means to display normally a given indication but to display a different indication when there is a magnetizable body adjacent said bars.

10. In combination, a pair of bars of magnetizable material located adjacent and parallel 25 to each other, means for constantly magnetizing one of said bars in a given direction and for constantly magnetizing the other of said bars in the opposite direction, other means for periodically varying the magnetic flux in said bars, and contacts controlled by said periodic variations of magnetic flux to periodically close and open and controlled by the magnetic flux in said bars as influenced by a magnetizable body adjacent said bars to remain constantly closed.

35 11. In combination, a pair of bars of magnetizable material located adjacent and parallel to each other, means for constantly magnetizing one of said bars in a given direction and for constantly magnetizing the other of said bars in the 40 opposite direction, means for periodically varying the magnetic flux in said bars alternately, a winding around each of said bars, and indication means controlled by variations in alternating current supplied through said windings in accordance with said periodically varied magnetic flux to display normally a given indication, but controlled to display a given different indication in response to modification of said flux by a magnetizable body adjacent said bars.

50 12. In combination, a pair of bars of magnetizable material located adjacent and parallel to each other, means for constantly magnetizing one of said bars in a given direction and for constantly magnetizing the other of said bars in the 55 opposite direction, a winding around each of said bars, a first and a second resistor, a bridge including one of said windings in series with one of said resistors as one side of the bridge and including the other of said windings in series with the other of said resistors as the other side of said bridge, means for passing alternating current through said two sides of said bridge in multiple with each other, means for periodically varying the alternating current passing through 60 one of said resistors, and contact means controlled by a circuit connected across the mid points of said bridge one of which is between one of said windings and the resistor with which it is in series and the other of which is between the other winding and the other resistor and periodically operated in response to said variations in alternating current but constantly operated in response to change in magnetic flux in said bars produced by a magnetizable body adjacent 70 75 said bars.

11

13. In combination, a pair of bars of magnetizable material located adjacent and parallel to each other, means for constantly magnetizing one of said bars in a given direction and for constantly magnetizing the other of said bars in the opposite direction, means for periodically reducing the magnetic flux in said bars alternately, a control winding around each of said bars, and a polar biased relay controlled by alternating current passed through said control windings as influenced by the periodic reductions in magnetic flux in said bars to close its contacts in a normal or a reverse position alternately and to close its contacts constantly in the normal or the reverse position in response to a magnetizable body adjacent said bars.

14. In traffic protection apparatus for a stretch of railway track, the combination comprising, a pair of bars of magnetizable material located adjacent said stretch of track, means for constantly magnetizing one of said bars in a given direction and for constantly magnetizing the other of said bars in the opposite direction, a control winding around each of said bars, a magnetizable core, a magnetizing coil around said core, a second magnetizable core, a second magnetizing coil around said second core, a circuit including a source of current and the control winding for one of said bars and also including asymmetric means and said first and second magnetizing coils all in series, a second circuit including a source of current and the control winding for the other bar and also including asymmetric means and said first and second magnetizing coils all in series, an output winding around said first core, a second output winding around said second core, and traffic governing means controlled by said first and second output windings.

15. In traffic protection apparatus for a stretch of railway track, the combination comprising, a pair of bars of magnetizable material located adjacent said stretch of track, means for constantly magnetizing one of said bars in a given direction and for constantly magnetizing the other of said bars in the opposite direction, a control winding around each of said bars, a magnetizable core, a magnetizing coil around said core, a second magnetizable core, a second magnetizing coil

12

5 around said second core, a circuit including a source of current and the control winding for one of said bars and also including said first and second magnetizing coils all in series, a second circuit including a source of current and the control winding for the other bar for passing current through said first and second magnetizing coils in the opposite direction to current in said first circuit, and traffic governing means controlled by magnetic flux produced in said magnetizable cores by said first and second circuits.

16. In combination, a pair of bars of magnetizable material located adjacent and parallel to each other, means for constantly magnetizing one of said bars in a given direction and for constantly magnetizing the other of said bars in the opposite direction, a control winding around each of said bars, a magnetizable core, a magnetizing coil around said core, a second magnetizable core, a second magnetizing coil around said second core, a circuit including a source of current and the control winding for one of said bars for passing current in a given direction through said first and second magnetizing coils, a second circuit including a source of current and the control winding for the other bar for passing current in the opposite direction through said first and second magnetizing coils, a bias winding around each of said cores, means for energizing said bias windings for producing magnetic flux in said first core in the same direction as the flux produced by said first circuit and for producing magnetic flux in said second core in the same direction as the flux produced by said second circuit, and indication means controlled by the magnetic flux produced in said magnetizable cores.
